UNITED STATES PATENT OFFICE

HENRY E. WHIPPLE, OF LOS ANGELES, CALIFORNIA

CRUSHING MILL

Application filed October 29, 1928. Serial No. 315,337.

This invention relates to mills for wet or dry crushing of any kind of materials to any desired degree of fineness.

The objects of the invention are to render such mills more efficient in operation; to increase the speed at which the mill may be driven and the materials crushed; to reduce the power for operating the mill, to eliminate wear of the crushing members and the mill lining; to eliminate dust due to the crushing action; to reduce the total weight of the mill and the freight charges for shipment of the same, and to make the mill operative for carrying out either the wet or the dry process of crushing. The manner in which these several objects are attained will be more fully set forth hereinafter.

The accompanying drawings show one form of my invention, but it is to be understood that the principles of the same may be embodied in different structures and that the claims hereof are not intended to be limited to the exact structure shown any farther than the specific terms employed render such limitation necessary.

In the drawings, Figure 1 is a central longitudinal and vertical section taken centrally through the mill showing the discharging means employed when the mill is used for wet crushing; Fig. 2 is a transverse vertical section through the mill taken on the broken line 2-2 of Fig. 1 and looking in the direction of the arrows, parts of the liner and of the crushing rollers being broken away to show the recesses or pockets therein; Fig. 3 is a sectional view taken centrally through the discharging means which is used when crushing by the dry process, and Fig. 4 is a transverse sectional view taken through Fig. 1 on the line 4-4 thereof and looking in the direction of the arrows.

The mill herein shown is of the rotary type comprising a rotatable drum having an interior cylindrical crushing surface upon which the materials are crushed by members loosely

positioned within the drum. Heretofore it has been common to use metallic rods of relatively small diameter as crushing members, these rods being used in a considerable number so as to tumble over each other as the drum rotates, thereby crushing the materials between themselves as well as upon the crushing surface of the drum. This tumbling action of the rods results in rapid wear, and it requires much power to lift the rods to that position where they will tumble. Moreover, the individual rods are relatively light and exert but a correspondingly small crushing force. Consequently, mills of that character perform their work slowly and require a great deal of power for their operation. As will be seen, I have largely eliminated the element of wear and have greatly reduced the power necessary for operation.

Taking up a detailed description of the invention as shown in the drawings, 5 represents the shell of the drum, and 6 the lining therefor. As shown, the lining is made up of a plurality of ring-like members made preferably of cast steel or rolled plate. 70 When assembled within the shell, these lining members form a substantially continuous cylindrical body having an interior cylindrical surface which forms one of the active elements in the crushing operation. For reasons more fully stated hereinafter, the sections of the liner 6 are provided with recesses or pockets 7, those at the right hand or feeding end of the drum being more closely spaced than those farther toward the left, while the pockets 7 toward the left extend but partially through their respective lining members.

The right hand end of the drum is closed by the feed-head 8 to which is attached an interior end liner 9, the latter having a flared opening at the center and at the axis of the drum, as shown at 10. Bolted, or otherwise secured, to the feed-head 8 is a large spur gear 11 through which the drum is rotated from any suitable source of power. The

head 8 is further provided with a tubular trunnion extension 12 which turns upon a bearing member 13, the latter being supported upon a suitable pillar or standard 14. 5 The bearing 13 is provided with a liner 15 on its lower side within which the tubular extension 12 of the head rotates. The upper part of the bearing is closed with a suitable member 16 having a closure cap 17, the member 10 and cap providing a chamber within which oiled waste may be packed for lubricating purposes. The bearing 13 thus supports the drum at one of its ends, while the other end is supported by rollers 18 upon which a 15 steel tire 19 rolls. But one of these rollers is shown in the drawings.

The tubular bearing 12 is closed at its outer end by a hollow member 20, the same having an opening 21 in the axial line of the drum 20 through which the materials to be crushed may be fed. The interior of the member is divided by a partition 22, inclined to the axis of the drum, as shown, said partition being provided with an opening 23. When the 25 parts are in the position shown in Fig. 1, the materials entering through 21 fall to the lower part of the member 20. As the drum with the said member is rotated, these materials pass through the opening 23 and into a 30 screw feeding device 24 within the tubular bearing, said device being provided with the screw threads 25 which work the materials toward the left until they pass through the flared opening 10 of the end liner and enter 35 the drum proper.

Near the left hand or the discharge end of the drum there is an annular lining member 26, the same being shown, in part, in Fig. 4. This member is provided with a series of 40 apertures 27 which are elongated, as shown in Fig. 4, with their longer axes making angles with the radii extending from the axis of rotation, as shown in Fig. 4. The openings 27 are closed by screens 28 in order to 45 hold back the coarser particles of the materials so that they will be discharged back into the drum for further crushing. The discharge end of the drum is closed by a head 29, said head being secured to the drum by 50 any suitable means, as by the bolts 30. Between the head 29 and the discharge-liner 26 there is an elevator 31, part of the same being shown in section in Fig. 4. This elevator is a hollow annulus with transverse partitions 32 therein so arranged as to form a 55 series of pockets 33, the side of the elevator adjacent the discharge lining 26 being provided with a series of apertures 34 registering with the apertures 27 in the said liner. 60 The construction of the parts just described is such that the crushed materials pass through the apertures 27 and 34 and through the screens 28 into the pockets 33 of the elevator in which they are lifted as the drum 65 and the elevator rotate. The partitions 32

extend in directions parallel with the longer axes of the apertures 27 and 34, and the materials in the pockets are carried upwardly by said partitions and are discharged by gravity downwardly toward the axis of the 70 drum.

Figure 1 shows the invention adapted for use with wet materials. In this structure, the finely crushed materials which pass the screens 28 and which are lifted by the elevator 31, are deposited into a discharge pan 35, the outer end of which is open so that the materials may run out into a launder 36 to be conducted away as desired. The launder 36 and the discharge pan 37 are rigidly 75 connected together, as by the rivets 37, so that the two may be handled together. The inner end of the discharge pan is closed by an upwardly extending plate 38 to prevent any of the finished materials from reentering 80 the drum. Secured to the plate 38 on its inward side is a flanged member 39, the lower portion of the flange being turned downwardly as shown. This member turns backwardly into the interior of the crushing portion of the drum any coarser materials which may fall upon the inclined flange, which flange is designated 39^a on Fig. 1 of the drawings.

Within the drum and in rolling contact with the crushing surface of the liner 6 is a large cylindrical crushing roller 40. While the size of this roller may vary, it is desirable that its diameter be as large as practicable in order that it may have an extended surface in crushing relation with the liner 6 upon which it rolls. If this roller were merely a metal bar, the crushing surface thereof would be little more than a mere line. This effective crushing surface increases with the diameter of the roller and consequently, the latter is made large, as stated. In practice, the ratio of the diameters of the crushing surface of the drum and of the roller is not greater than six to one. In other words, the roller should have a diameter at least one-sixth as great as the diameter of the cylindrical surface upon which it rolls. Further, the large roller has great weight so as effectually to crush the materials over which it rolls. The roller 40 is preferably made hollow, as shown, and its inner surface provides a second crushing surface upon which rolls a second crushing cylinder or roller 41. The diameter of the second cylinder is preferably made as 100 large as practicable for the reasons stated in connection with the roller 40. That is to say, the roller 41 will then have an extensive effectual crushing area cooperating with the inner crushing surface of the roller 40, and it will also possess the necessary weight for 105 crushing the materials.

Preferably, the roller 41 is also a hollow cylinder, the inner surface of which forms a third crushing surface upon which rolls a 110 115 120 125 130

third crushing roller 42. For mills of ordinary size, the three rollers 40, 41 and 42 are sufficient. Therefore, there will be no interior crushing surface required in the roller 42, and it is made solid in order to give it the requisite crushing weight. At its feed end, however, it is provided with a recess or chamber 43 opening outwardly to receive the materials which enter through the feeding apparatus. These materials pass outwardly from the chamber through passages 44 onto the inner crushing surface of the roller 41 so as to be first subjected to the crushing action of the roller 42. As will be understood, the crushing weight applied to the materials on the surface of the liner 6 is substantially the combined weights of all the rollers. In small sized mill and where the materials are easily crushed, fewer rollers will suffice.

The roller 40 is provided with a series of passages 45 extending through it in a generally radial direction, as shown in Fig. 2, and the roller 41 is provided with similar passages 46. These passages not only permit the crushed or partially crushed materials to pass through them during the crushing operation, but they lift the materials for some distance and then discharge them inwardly to be further acted upon. In order that they may more effectually perform the last stated function, the passages do not extend through the rollers in straight radial direction, but are angular in shape, as shown in Fig. 2. This angularity results in the formation of cups or pockets which hold the materials until the pockets have turned about and are well toward the top of the rollers. The materials from the pockets of the roller 40 are thus discharged upon the outer surface of the roller 41 and are distributed over said surface in best condition for further crushing action by said roller. In like manner the cup shaped passages 46 of the roller 41 carry the materials upwardly and distribute them upon the surface of the roller 42. In the same way, the pockets 7 and 7' in the liner 6 carry up the crushed materials and pour them out upon the outer surface of the drum 40.

During operation, the finely crushed materials are constantly discharging through the screens 28 into the elevator 31. These materials pass freely through the screens with the result that there is less material present toward the discharge end of the drum than there is at or near the feed end. Consequently, there is more material to be elevated at the feed end, and the pockets or recesses 7, 45 and 46 are spaced more closely together at and near the feed end than they are toward the discharge end. In fact, the pockets 7' in the liner do not need to extend through to the shell, since they have suffi-

cient capacity when constructed as shown in Fig. 1.

When the crusher is employing the dry process of crushing, the crushed materials may be more effectually discharged or withdrawn by means of a fan. If they were discharged by the open pan and launder 35 and 36, much dust would escape, which would be not only an economic loss but would so fill the air as to make it difficult for workmen. However, it is desirable that all the parts used in the wet process, except the discharge pan and launder, be also used in the dry process. The said pan and launder are therefore made easily detachable or removable from the mill, while the discharge head 29 is provided with a flange 47 to which the housing 48 of the discharge fan 49 may be readily attached. To the fan housing 48 there is secured a housing 49 for the electric motor 50, the armature shaft of said motor being suitably journaled in the housing 49 and in a partition member 51 which separates the fan housing from the motor housing. When the fan is driven, the air is drawn out of the drum, being discharged through a passage which is led from the fan housing about the motor housing, as indicated in dotted lines in Fig. 3 and is then curved into a discharge tube 52, the axis of which coincides with the axis of the motor and of the drum of the crushing machine. It will be understood that the flange 47 of the discharge drum-head turns the housings for the fan and motor, so that all of these parts rotate as a unit about the axis of the drum. For disposing of the finely crushed material drawn outwardly by the fan, the discharge tube 52 is connected with a suitable conveying pipe, not shown, which leads to any desired receiver for the crushed material.

As stated, before the fan housing is attached to the head-flange 47, the discharge pan and launder 35 and 36, used in the wet process, are removed. This provides ample space for the members shown at the right in Fig. 3 which project through the discharge head 29, and through the elevator 31. These members consist of an annulus 53, which is attached to the fan housing in any suitable manner, as by means of bolts 54. The annulus 53 is provided with a series of projecting fingers 55, the same forming a tapered cage or skeleton over which there is placed a screen 56. All materials which are lifted by the elevator 31 are deposited upon this screen, and any of them which are fine enough to pass through the meshes of the screen are drawn outwardly by the fan. The particles which are too coarse to pass through the screen move inwardly along the tapered surface of the screen and drop back into the drum proper so as to be further acted upon by the crushing rollers. To facilitate this movement of the coarser particles to-

ward the drum proper, spirally shaped vanes 57 are provided, the same being given such shape as will cause the coarser particles to travel in the desired direction. The very fine particles do not ordinarily pass through the screens but are drawn by the fan directly into the open end of the cage 55.

Owing to the large diameters of the rollers with respect to the surfaces upon which they roll, there is substantially a true rolling action and but little wear. Moreover, the rollers turn when the drum has moved but slightly from its position of rest, as indicated in Fig. 2, so that the rollers are not lifted far above their lowermost positions. Consequently, relatively little power is required to start the rollers turning and to maintain the rolling action. For this reason, my invention results in a great saving of power as well as in a great reduction of wear. If desired, the third or inner roller may be omitted and the materials fed directly into the open end of the second roller. In such a structure the said second roller 25 would be made heavier to increase its crushing action and, preferably, its walls would diminish in thickness from the feed toward the discharge end to cause the materials to move in that direction. At the discharge 30 end the roller may be provided with a bead or flange extending inwardly and serving as a low dam to hold back the materials until they pass outwardly through the peripheral openings. Such a structure is so obvious 35 from the foregoing description that it is not deemed necessary to add to the drawings by an illustration of it.

Since the operation of the mill involves nothing but the rolling of surfaces one over 10 the other, the mill may be driven at a high rate of speed without undue jar. In view of all of these facts, a mill embodying the invention herein disclosed is capable of doing as much work as a much larger, heavier 45 and more expensive mill built upon any other principle known to applicant.

While the drawings disclose plain or smooth contacting surfaces on the liner and on the drums, these surfaces may be corrugated or finished in any other desired pattern.

For furnishing current to the electric motor 50, the discharge tube 52 is provided with the necessary contact rings for brushes, one of such rings being indicated at 58.

Having thus described my invention, what I claim as new and desire to secure by Letters Patent is:—

1. In a crushing mill, the combination with a hollow rotatable member the interior surface of which forms a cylindrical crushing surface, of a crushing roller within the hollow of said member and having rolling contact with the crushing surface thereof as the member rotates, said roller being provided 65 with a pocket at one end and with passages

leading therefrom to the surface of the roller, whereby the material to be crushed may be fed into said pocket and through said passages so as to be crushed between said roller and said crushing surface, means for feeding the material to be crushed into said pocket, and means for removing the crushed material. 70

2. In a crushing mill, the combination with a hollow rotatable member having an interior cylindrical crushing surface, of a hollow crushing roller within the said member and having rolling contact with said surface as the member rotates, the interior of the hollow roller forming a second cylindrical crushing surface, a crushing roller within the hollow of the first mentioned roller and having rolling contact with the crushing surface thereof, the last mentioned roller having a pocket therein and passages leading from the pocket outwardly to the surface of the said last mentioned roller, means for feeding the material to be crushed into the said pocket, and means for removing the crushed material. 75

3. In a crushing mill, the combination with a rotatable drum having an interior cylindrical crushing surface, of a hollow crushing roller within the said drum and having rolling contact with said surface as the drum rotates, the interior of the hollow roller forming a second cylindrical crushing surface, a second hollow crushing roller within the first mentioned roller and having rolling contact with the crushing surface thereof, the interior of the said second roller forming a third cylindrical crushing surface, a third crushing roller within the hollow of the second roller and having rolling contact with the crushing surface thereof, said third roller having a pocket therein and passages leading from the pocket outwardly to the surface of the said third roller, means for feeding the material to be crushed into the said pocket, and means for removing the crushed material from the drum. 90

4. In a crushing mill, the combination with a hollow rotatable drum, of means within said drum for crushing material fed thereto, a head at one end of the drum, means connected with said head for feeding material to be crushed into said drum, a second head at the other end of the drum, a housing connected to said latter head, a fan and a motor for driving the same within said housing, the housing, fan and motor rotating with the said drum, and means connected with the said housing for conducting the finely crushed material from the drum, said fan acting to draw said material from the drum and to discharge it through said conducting means. 105

5. In a crushing mill, the combination with a hollow rotatable drum, of means within said drum for crushing material fed thereto, a head at one end of the drum, means connected 115

with said head for feeding materials to be crushed into said drum, a second head at the other end of the drum through which the crushed material may be discharged, and 5 means on the second head for attachment of a fan housing.

6. In a crushing mill, the combination with 10 a hollow rotatable drum, of means within said drum for crushing material fed thereto, a head at one end of the drum, means connected with said head for feeding materials to be crushed into said drum; a second head at the other end of the drum through which the crushed material may be discharged, 15 means rotatable with the drum between the second head and the crushing means for lifting the crushed material and discharging the same toward the axis of rotation, and means on the second head for attachment of a fan 20 housing.

7. A crushing mill comprising a rotatable drum having an interior cylindrical crushing surface, a hollow crushing roller within the said drum and having rolling contact with 25 said surface as the drum rotates, a hollow trunnion supporting said drum at one of its ends, the hollow of the trunnion having open and unobstructed communication with the hollow of the roller, means for feeding material to be crushed through said hollow trunnion and for discharging the same directly 30 into the hollow of the roller, means for rotating the drum and means for removing the crushed material from the drum.

8. A crushing mill comprising a rotatable drum having an interior cylindrical crushing surface, a hollow crushing roller within the said drum and having rolling contact with said surface, the interior of the hollow roller 40 forming a second crushing surface, a second hollow roller within the first mentioned roller and having rolling contact with the said second crushing surface, a hollow trunnion supporting said drum at one of its ends, 45 the hollow of the trunnion having open and unobstructed communication with the hollow of the said second rollers, means for feeding material to be crushed through said hollow trunnion and for discharging the same directly 50 into the hollow of the second roller, means for rotating the drum and means for removing the crushing material from the drum.

9. A crushing mill comprising a rotatable 55 drum having an interior cylindrical crushing surface, a hollow crushing roller within the said drum and having rolling contact with said surface, the interior of the hollow roller forming a second crushing surface, a 60 second hollow roller within the first mentioned roller and having rolling contact with the said second crushing surface, the interior of the second hollow roller forming a third surface, a third roller within the second roller 65 and having rolling contact with the crush-

ing surface thereof, said third roller having a pocket formed at one of its ends, a hollow trunnion supporting the drum at one of its ends, means for feeding material to be crushed through the said hollow trunnion and 70 for discharging the same directly into the pocket of the third roller, means for rotating the drum and means for removing the crushed material from the drum.

In testimony whereof I have signed my 75 name to this specification.
